UNITED STATES PATENT OFFICE.

FRED F. HEDDEN, OF LOS ANGELES, CALIFORNIA.

STEPLADDER.

1,377,579.

Specification of Letters Patent. Patented May 10, 1921.

Application filed January 9, 1920. Serial No. 350,465.

To all whom it may concern:

Be it known that I, FRED F. HEDDEN, a citizen of the United States, residing at Los Angeles, in the county of Los Angeles and 5 State of California, have invented new and useful Improvements in Stepladders, of which the following is a specification.

This invention relates to ladders and particularly to ladders that are adapted for use 10 in fields, orchards or in other conditions of use in which the feet portions thereof may be arranged on supports not in a common plane, and has for its object to improve the construction of step ladders so as to facilitate 15 the stabilization of the same in various positions for a reliable foundation, and the invention consists of the construction and details an embodiment of which is illustrated in the accompanying drawings and 20 described and claimed herein.

The present step ladder is an improvement on the form of step ladder disclosed in Patent 1,087,286, to A. H. Franklin, dated February 17, 1914. In that patent the struts 25 or legs were provided for independent lateral movement with respect to each other, but were not provided with independent adjustment with respect to the plane of the step ladder frame proper both of the steps or 30 struts of the set adapted to swing on a common axis toward and from the ladder frame, and the present invention has for one object to provide for the independent adjustment of one leg with respect to the other toward 35 and from the plane of the frame of the ladder and as to each other and also independently angularly adjustable with respect to the longitudinal axis of the frame.

Figure 1 is a perspective showing the ladder 40 as arranged in one position of use.

Fig. 2 is a detail sectional view of the upper portion of the ladder frame showing the independent mountings of each of the struts or legs.

Fig. 3 is a section on line 3—3 of Fig. 2 showing details of construction.

Fig. 4 is a detail perspective of a fragment of the ladder frame with a portion of one of the leg hangers.

Fig. 5 is a detail transverse section illustrating in plan a form of clip to retain the legs in retracted position.

The device comprises a ladder frame having a series of treads 2 connected by side 55 stringers 3 and having a top tread or plat-

form 4, these elements being of suitable construction, proportion and material and forming a rigid frame adapted to be supported in a suitable upright position conveniently with respect to an uneven supporting surface of configuration through the proper adjustment of suitable legs or struts 5—5.

To secure the efficient adjustment of this ladder in various installations it is preferable that the legs 5—5 be adjustable entirely independent of each other toward and from the plane of the ladder frame 3 and also laterally toward and from the longitudinal axis of the main frame, and to that 65 end each of the legs 5 is connected to an independent hanger, in the present case, comprising a toothed segment 6 having a radial bar 7 at one side with projecting studs or bearing members 8—8 adapted to suitable 70 bearings 9 of which an appropriate number is shown as attached to the lower surface of the platform or top step 4. The hanger segment 6 is also provided with an arm 7' for rigidity of construction, this arm 75 being substantially at right angles to the axle forming arm 7, and a pair of the frames 6 is utilized, in the present case, one for each leg 5, the frames being set with their arms 7' in juxtaposition and with the adjacent 80 pivot studs or shaft ends 8 in a common intermediate bearing 9.

The legs 5 are respectively connected to their frames 6 in suitable manner, in the present case comprising a pivot pin 11 at the 85 upper end of each leg, this pin extending through a radial slot 12 at the base of the arm 7' so that the leg can be lifted or have slight play with respect to its hanger 6 in order to permit the interlocking with the 90 teeth of the segment 6 of a pin 13 mounted in the leg 5 at such position as to engage the toothed surface 14 of the segment.

For rigidity of construction and durability the pins 11 and 13 are shown as passed through a U-shape support 15 between the spaced arms of which the segment 6 may ride when the leg 5 is swung from or toward the longitudinal axis of the ladder as on the upper pivot pin 11 in the slot 12. 100 The object of the slot is to permit the movement of the locking pin 13 from or toward the teeth 14 in the angular adjustment of the leg laterally of the frame of the ladder. As soon as the legs 5 have been set in their 105 110

relative angular adjustment to each other and also set in independent angular relation with respect to the plane of the frame 3 5 the legs become automatically locked by the interengagement of the pins 13 with the teeth 14 of the segments and the whole therefore rigidly connected and capable of bearing a load on the ladder.

From this it will be seen that it is possible 10 to swing the legs 5—5 independently toward and from the plane of the ladder frame 3 and also to swing them independently and toward each other or toward and from the longitudinal axis of the ladder at any angular position of the legs with respect to the plane of the frame of the ladder.

The legs 5—5 may be temporarily locked or retained in contracted position by means 20 of a suitable device as a yielding clip or receiver 16 that may be attached to one of the lower treads of the ladder frame, as shown in Fig. 5.

The swinging movement of the legs 5—5 about their pivots 11 can be limited by any 25 suitable means as for instance by inwardly deflecting one component or side of a member 15 as at 15^a.

Various changes may be made without departing from the spirit of my invention as 30 claimed.

I claim:

1. A step ladder having a step frame, legs

universally hinged to said frame to move independently of each other, and means to lock said legs in lateral adjustment. 35

2. A step ladder having a step frame, hinges secured to said frame, legs universally hinged to said frame by said hinges to move independently of each other, said hinged means having means thereon to lock 40 said legs in lateral adjustment.

3. A step ladder having a step frame, legs universally hinged to said frame to move independently of each other, the hinge means comprising individual segmental 45 members hinged to said frame along one side, legs pivotally mounted on said hinge members, notches in the arcuate portions of each member, and means on the legs co-acting with said notches to secure them against 50 lateral movement.

4. A step ladder having a step frame, segmental hinge members mounted on said frame adjacent its top to move independently of each other, legs pivotally mounted 55 on said hinge members to move laterally with reference to said frame, means on said hinge members to selectively adjust the legs laterally with reference to each other and with reference to the horizontal plane of 60 said frame.

In testimony whereof I have signed my name to this specification.

FRED F. HEDDEN.
